WINSLOW CLEMENT SPOUSTA, OF CHICAGO, ILLINOIS, ASSIGNOR TO WESTERN ELECTRIC COMPANY, INCORPORATED, OF NEW YORK, N. Y., A CORPORATION OF NEW YORK

ASSEMBLING ARTICLES FOR TRANSPORTATION

Application filed April 10, 1929. Serial No. 354,002.

This invention relates to assembling articles for transportation, and more particularly to grouping articles for transportation in such a way that they may be unloaded expeditiously.

An object of this invention is to provide a simple and economical method for assembling articles for transportation.

In accordance with this object one embodiment of the invention comprises a method of assembling articles, such as lead pigs wherein a pair of metallic straps are extended longitudinally of the floor of a freight car. A pair of wooden strips are then placed along and on top of the straps and a stack of the articles deposited on the strips. Another pair of similar strips are then positioned on top of the straps abutting the first strips and a second stack of the articles deposited thereon. The placing of strips and depositing of stacks of the articles are carried out until one end of the car is filled with a continuous row of stacks when the ends of the metallic straps are bent around the ends of the row and over the top thereof and clamped to secure the several stacks together as a unit. The row is separated from the walls of the car and from other similar rows so that it may slide or shift freely on the car floor when the car is jolted at either end, and the articles do not tend to roll but remain in their original stacked position so they may be removed at their destination by the same type of handling device that loaded them.

This and other objects of the invention will become apparent from the following description of one embodiment of the invention when taken in connection with the accompanying drawings, wherein

Fig. 1 is fragmentary perspective view of a freight car or other suitable means for transporting lead pigs in which a pair of metallic straps and wooden strips or boards are shown positioned longitudinally of the car as in the first step of the method;

Fig. 2 is a similar view disclosing stacked bars of lead deposited upon the floor boards as in the second step of the method;

Fig. 3 discloses a completed row of the

stacks bound together by means of the metallic straps, and

Fig. 4 is a fragmentary side view of one end of the row, showing a strip that may be inserted beneath the vertical portion of each strap to maintain the end of the row straight.

Referring now to the drawings in which like numerals designate similar parts in the several figures, there is disclosed a pair of metallic straps 5, such as strap steel, which are positioned longitudinally of the floor 6 of one end of a freight car and temporarily attached thereto by staples 7 and extended upwardly along the end 8 of the car and temporarily attached thereto by staples 9. The straps 5 are placed at one side of the car, as shown, so that a number of, usually three, pairs of such straps may be positioned in one end of the car, and the straps are spaced at some distance from the side 10 of the car.

The straps 5 form the means whereby bars of metal, such as pigs of lead or similar articles, are held together and protected from the jolts of the car, as will appear as this description progresses. With the straps temporarily attached as aforesaid a pair of wooden strips or boards 13 of a length equal to the length of the stack of pigs to be sustained thereby are laid over and along the straps at one end of the car, but at some distance from the end 8, as shown in Fig. 1, to provide for movement of the stacks of pigs lengthwise of the car without contacting with the end thereof.

A stack of pigs, piled as shown in Fig. 2, in the manner in which they were positioned at the refinery with the pigs in one layer arranged transversely to the pigs of the adjoining layer and preferably seven layers high, is now brought into the car by any suitable means, such as a lift truck, which grips the stack underneath the ledges 14 of the lowermost layer, and deposited upon the boards 13. The pigs of the uppermost, as well as of the lowermost layer of the stack are arranged transversely of the straps 5 for the purpose of making firm contact with the straps 5 and the boards 13.

A second pair of boards 13 (Fig. 3) are now placed on top of and along the straps 5

and abutting the ends of the boards of the first stack and another stack of pigs piled similarly to those of the first stack is deposited thereon in close proximity or in contact with the first stack. Thus, at this stage 5 of the loading there are two adjoining stacks of pigs positioned longitudinally of the car and resting upon separate pairs of successive boards 13. The boards 13 are separate so they do not interfere with the loading and 10 unloading of the stacks.

Additional stacks of similarly piled pigs (Fig. 3), with the uppermost and lowermost layers arranged transversely of the straps 5 and the boards 13, are deposited by truck 15 in the manner aforesated longitudinally of the car and adjoining the previous stack until a complete row of contiguous stacks is produced which extends up to the car door. This is as far as it is practical for loading 20 purposes to extend the row, and the staples 7 and 9 for temporarily securing the straps 5 to the car are now removed and the straps 5 are bent up around the ends and over the 25 row of stacks and the ends of the straps are firmly clamped together at 15 to bind all of the stacks together in one continuous row or unit. Other similar rows, usually two, are now positioned alongside of this row in the 30 same manner at some distance from the end of the car, and then at the other end of the car three other similar units are positioned. Care is taken to see that the units are separated from each other and from the car 35 ends and sides so the units may be free to move when the car is jolted or jammed at either end.

By this method of grouping the stacks of pigs, the boards 13 extending longitudinally 40 of the car floor 6 provide for movement of the stacks along the floor rather than the rolling of pigs and stacks over each other and toward one end of the car when the car is jolted, since if the pigs were placed directly on the 45 car floor they would not tend to slide because of their great weight and their frictional contact with the irregular surface of the car floor. If the stacks were placed directly on the car floor the lower layers of the stacks 50 tend to remain stationary when the car is jolted and the upper layers roll over the lower ones. By positioning the boards 13 underneath the stacks, the stacks and boards 13 move along the floor as a unit upon any substantial 55 jolt of the car and there is no tendency for any of the lead pigs to roll. The metallic straps 5 operate to secure the individual pigs in position while the stacks are thus sliding on the boards 13 along the car floor.

60 Thus, with this method of providing for sliding of the stacks by means of the boards 13 and the securing and binding of the lead pigs and stacks together by means of the straps 5, the stacks of pigs arrive in the same 65 condition in which they were originally posi-

tioned in the car and the individual stacks may readily be removed in the same manner in which they were deposited in the car by extending the forks of a lift truck underneath the lowermost ledges 14 of each stack and removing the stack without having to replace any of the pigs. The lift truck readily removes one stack after another in the same manner that it loaded the pigs and there is no manual handling, restacking, rearranging, or replacing of the piles or pigs and no possible injuries resulting to operators in the manual handling necessitated where the stacks are not so orderly retained in position. 70 75

Whenever the car is subjected to a jolt or jar at either end it is to be understood that the individual stacks of pigs thus grouped together on the boards 13 and bound by the straps 5 slide longitudinally of the car rather than being subjected to the suddenness or abruptness of the shock because the boards provide for easy sliding of the stacks on the car floor and the rows or composed units of stacks are spaced from each other and from the sides and ends of the car to allow for this 80 sliding movement. The different groups of stacks never come in contact with each other or the car ends or sides and slide as a unit rather than being jolted or rolled as they would if they were held or bound to some 85 specific position, and thereby the pigs and stacks remain intact and in a condition for 90 unloading at the destination without any rearranging. 95

From the foregoing description it is believed to be apparent that this novel method provides a simple and economical way of 100 shipping bars of metal or of grouping and supporting articles in a car so that the bars or articles arrive at destination in the same condition in which they were loaded and may be removed by the same kind of handling device that was used in loading. An optional 105 way of maintaining the bound unit straight at its ends is shown in Fig. 4, which consists of inserting a strip 17 beneath the vertical portion of each strap 5 to bind against the end of the row. 110

It is of course to be understood that the invention is not to be limited by the specific embodiment herein described and illustrated, but is to be limited only by the scope of the appended claims. 115

What is claimed is:

1. A method of assembling articles in a car 120 for transportation, consisting in grouping the articles in individual units for handling, positioning boards on the floor of the car for receiving the individual units, depositing the individual units upon the boards, and binding 125 the individual units together with the boards into larger units.

2. A method of assembling articles for transportation, consisting in stacking the articles in individual piles for handling, posi- 130

tioning the individual piles upon boards, and binding the individual piles and boards into large units for transportation.

3. A method of assembling articles for transportation, consisting in grouping the articles in individual units for handling, positioning the articles upon individual boards, and arranging the individual units and individual boards into larger units for transportation.

10 4. A method of assembling articles in a car for transportation, consisting in extending straps longitudinally of the car floor, placing boards on the straps, depositing the articles on the boards, and banding the articles and boards together by bending the straps around the articles and clamping the straps together.

15 5. A method of assembling articles in a car for transportation, consisting in grouping the articles in individual units for handling, extending straps longitudinally of the car floor, placing boards of sufficient length to receive one of the individual units on the straps, depositing the unit thereon, placing similar boards on the straps for receiving a second unit of articles, depositing the second unit thereon, placing and depositing similar boards and units on the straps, and banding the several units and boards together into

20 a large unit by bending the straps up around the units and clamping the straps together.

25 6. A method of assembling articles in a car for transportation, consisting in positioning individual stacks of the articles with the articles of the uppermost and lowermost layers thereof disposed transversely of the car end to end and longitudinally of the car, and extending straps longitudinally of the stacks around said transverse layers to bind the

30 stacks together as a unit.

7. A method of assembling bars of metal in a car for transportation, consisting in grouping the bars in units for trucking, positioning boards longitudinally of the floor of the car so the units may move longitudinally thereof, depositing the units adjacent each other upon the boards, and securing the bars in position in the units.

35 8. A method of assembling bars of metal in a car for transportation, consisting in extending a pair of straps longitudinally of the car floor, placing boards along and on the straps, depositing the bars of metal in stacks upon the boards, and securing the bars of each stack in position by bending the ends of the straps up around all of the stacks and clamping the straps.

40 9. A method of assembling articles in a car for transportation, consisting in extending a plurality of spaced straps longitudinally of the car floor, placing a plurality of boards along and on the straps, positioning individual stacks of the articles upon each board, the boards and stacks being in abutting end relation, and banding the several stacks

and boards together into a large unit by bending the straps up around all of the stacks and clamping the straps together.

In witness whereof, I hereunto subscribe my name this 28th day of March, A. D., 1929. 70

WINSLOW CLEMENT SPOUSTA.
